US0D1071334S

(12) **United States Design Patent** (10) **Patent No.:** **US D1,071,334 S**
Zhou (45) **Date of Patent:** **** Apr. 15, 2025**

(54) **ARTIFICIAL EYELASH EXTENSION
APPLICATOR**

(71) Applicant: **Yin Zhou**, Jiaozhou (CN)

(72) Inventor: **Yin Zhou**, Jiaozhou (CN)

(*) Notice: Patent file contains an affidavit/declaration under 37 CFR 1.130(b).

(**) Term: **15 Years**

(21) Appl. No.: **29/952,979**

(22) Filed: **Jul. 18, 2024**

(51) LOC (15) Cl. **28-03**

(52) U.S. Cl.

USPC **D28/55**

(58) **Field of Classification Search**

USPC ..... D28/4, 7, 9, 10, 35, 36, 39, 55, 57, 93, D28/99; D8/52; D24/133, 143; 132/217, 212, 216, 218, 286, 320, 333 CPC A45D 2/48; A45D 2/00; A45D 2002/003; A45D 6/00; A45D 7/00; A45D 8/00; A45D 2200/00; A45D 26/00; A45D 26/0023; A45D 26/0066; A45D 44/00; B25B 9/02; G04D 1/021; A61B 2017/305; A41G 5/00; A41G 5/02; A41G 5/0053; A41G 5/004; A41G 5/0046
